UNITED STATES PATENT OFFICE.

PAUL J. NEITZEL, OF SOUTH BEND, INDIANA.

DESIGN FOR A GAME-BOARD.

SPECIFICATION forming part of Design No. 32,974, dated July 17, 1900.

Application filed June 13, 1900. Serial No. 20,213. Term of patent 7 years.

To all whom it may concern:

Be it known that I, PAUL J. NEITZEL, a citizen of the United States, residing at South Bend, in the county of St. Joseph and State 5 of Indiana, have invented and produced a new and original Design for a Game-Board; and I do hereby declare the following to be a full, clear, and exact description of the invention, such as will enable others skilled in the art to which it appertains to make and use the same.

My invention relates to designs for game-boards; and it consists in a board having raised sides, with a pocket in each corner, and 15 having marked upon the center of the board the squares used in games and having surrounding the checker-board figures of insects, birds, and animals and outside of the four rows of birds, insects, and animals a series of 20 banners or flags, all of which will be more fully described hereinafter.

The accompanying drawing represents a plan view of a design which embodies my invention.

25 A represents the game-board, which is rectangular in shape and having the raised edges B extending around its four sides and provided with a pocket C at each corner. The surface of this board is perfectly flat. In the 30 center of this board are formed the checker-board squares D, and upon the center of these checker-board squares is formed the square

F, which extends entirely across, at its corners, the space occupied by the checker-board squares D. Inside of this square is formed 35 the circle G, which extends across over lines of the checker-board squares, as shown. Extending horizontally across the checker-board squares and inside of the square F are the lines H, which divide the two central lines of 40 checker-board squares into triangular spaces I. Around the four edges of the checker-board squares are four lines of figures, each figure placed in a square of its own, representing birds, insects, fish, and animals, and 45 outside of each row of birds, insects, fish, and animals is arranged a line of flags or banners, which are placed between the rows of animals, insects, and birds and the outer raised edges B of the board A. In each of 50 the four corner-spaces of the checker-board squares is the figure of a man or boy, as shown, their heads being inclined inwardly toward the center of the board.

Having thus described my invention, I 55 claim—

The design for a game-board substantially as shown and described.

In testimony whereof I affix my signature in presence of two witnesses.

PAUL J. NEITZEL.
